Primary Examiner—Ted Shooman*Assistant Examiner*—Mitchell I. Siegel*Attorney, Agent, or Firm*—William W. Haefliger**[57] CLAIM**

The ornamental design for golf putter head with multi-arcuate configuration, as shown and described.

DESCRIPTION

FIG. 1 is a perspective view of a putter head embodying our new design;

FIG. 2 is a top plan view thereof;

FIG. 3 is a bottom plan view thereof;

FIG. 4 is a rear view thereof;

FIG. 5 is a front view thereof;

FIG. 6 is a toe end view thereof; and,

FIG. 7 is a heel end view thereof.
